US00D711293S

(12) **United States Design Patent**
Waterman et al.

(10) **Patent No.:** **US D711,293 S**
(45) **Date of Patent:** **** Aug. 19, 2014**

(54) **VEHICLE COMPONENT**

(71) Applicant: **Jaguar Land Rover Limited**, Coventry (GB)

(72) Inventors: **Jeremy Waterman**, Coventry (GB); **Andrew Wheel**, Coventry (GB)

(73) Assignee: **Jaguar Land Rover Limited** (GB)

(**) Term: **14 Years**

(21) Appl. No.: **29/466,420**

(22) Filed: **Sep. 6, 2013**

(30) **Foreign Application Priority Data**

Mar. 8, 2013 (EM) 002199307

(51) **LOC (10) Cl.** **12-16**

(52) **U.S. Cl.**

USPC **D12/163**

(58) **Field of Classification Search**

USPC D12/169, 196, 171, 163, 216, 90-92,

(57) **CLAIM**

The ornamental design for a vehicle component, as shown and described.

DESCRIPTION

FIG. 1 is a left front perspective view of a vehicle component; FIG. 2 is a right front perspective view of a vehicle component;

FIG. 3 is a left upper perspective view of a vehicle component;

FIG. 4 is a right rear perspective view of a vehicle component; FIG. 5 is a upper front perspective view of a vehicle component;

FIG. 6 is a front view of a vehicle component;

FIG. 7 is a side view of a vehicle component; and,

FIG. 8 is a perspective view of the vehicle component in the installed position on a vehicle.

Portions of FIG. 8 that are shown as broken lines are for illustrative purpose only and form no part of the claimed design.

1 Claim, 5 Drawing Sheets
